AUGUSTINE DAVIS, JR., OF CINCINNATI, OHIO

SIPHON APPARATUS

Application filed September 28, 1928. Serial No. 309,105.

The invention relates to siphon apparatus.

Siphonic discharge as applied to multiple compartment tanks, such as the tanks of tank trucks, is now carried out in the following manner. Conduits extend upward from near the bottoms of the several compartments to a point above the liquid level, whence they are carried downward for a distance to join a common conduit or manifold running lengthwise of the series of compartments, the delivery hose being attached to the rear end of this common conduit. Flow is started in this branched siphon by means of a hand pump placed in a by-pass of the outer portion of the common conduit, a manually operated valve being placed in parallel with the pump, and a check-valve being placed in the conduit beyond the pump. In order to withdraw liquid from one of the compartments and not from others it is necessary to provide valves for the several branches of the siphon, which can be opened and closed independently. The compartments contain measured quantities of liquid, and in order to avoid delivering either more or less than the proper amount to a customer, it is obviously necessary that all branches of the siphon but the one from which a delivery is being made be tightly closed.

Furthermore, starting the siphonic flow by a hand pump is made more difficult, or impossible, and the flow, when started, may stop, if there are leaks in the siphon or around the valves. The operativeness of such a plan is dependent, therefore, on the tightness of these valves, which as usually located have to be tight, not against liquid, but against air. The valves sometimes are not tight, or if originally tight may not remain so.

An object of the present invention is to provide a more satisfactory siphon system, in which the siphons of the several tank chambers are independent in respect to starting, or at least not dependent on the tightness of large valves in the siphons between the suction producing means and the compartments. A single exhausting or suction producing means is employed, with means for operatively connecting it with any one of the siphons, and a common discharge conduit is

preferably provided for permanent connection of a hose. The several siphon lines are provided, beyond the points of connection with the exhausting means, with check-valves, or other suitable valves, for preventing the inflow of air when the siphon is being started.

While it is true that these valves should be tight, which is even more necessary in the case of the single check valve of the existing system, there is an advantage in providing each siphon line with its check valve, since if one of these valves should leak it would affect only one siphon and not others.

The provisions for operatively connecting the exhausting means with the siphons may be varied. They preferably comprise permanent suction lines connecting the exhausting means with the several siphons at points between the air-excluding valves and the tank chambers, together with valve means for opening any one of the suction lines, the others remaining closed.

With such an arrangement I provide a selective valve control capable of opening, or permitting the opening, of any one of the suction lines to the exclusion of others, thereby guarding against discharging the contents of more than one tank chamber at a time.

Furthermore, I provide a selective control for the air-excluding valves.

In the existing system, gasoline is drawn through the pump at the beginning of flow. In accordance with my invention, the exhausting means is not in the path of liquid flow. I provide means which is controlled by the liquid to shut off the communication to the exhausting means, whatever its nature, automatically, so that the liquid does not enter or pass through the exhaustor.

Another object of the invention is to obviate the laborious operation of working a hand exhaust pump to start the siphon. To this end I provide a vacuum chamber, which can be exhausted either by a power pump on the vehicle at a time when deliveries are not being made, or which can be exhausted before the truck starts on its rounds. This chamber is connected with the siphons

to exhaust air therefrom, and constitutes a reservoir of potential energy sufficient for numerous startings.

Other aspects of the invention, however, 5 are not necessarily limited to the use of a vacuum reservoir, and the term "exhausting means" in the claims is intended to cover either such a chamber or a pump.

Other features of the invention will be 10 described in the body of the specification.

In the accompanying drawings, forming part hereof:

Fig. 1 is a side elevation of a truck tank embodying the invention;

Fig. 2 is a detail view principally in vertical section, at the top of one of the siphons;

Fig. 3 is a rear end elevation looking at the face of the control-box, part of the wall of the control-box and most of its door being 20 broken out to show parts within, and an enclosure in the interior being also partly broken away.

Fig. 4 is a side elevation of the tank with most of its intermediate part broken out, the 25 control-box being broken away and in section; and

Fig. 5 is a schematic view.

The drawing represents a truck tank 2 divided by partitions 3 into a number of 30 separate chambers 4. At the rear end there is a control box 5 having a door 6.

Pipes 7 extend upward from points near the bottom of the several chambers 4 to points above the liquid level. These siphon lines 35 are preferably carried to the rear end and down into the box 5, where they are marked 8.

In the lower part of the box there is a common pipe 9, to which all the siphon lines are 40 connected, the end of this pipe having a connection to which a delivery hose 10 is attached.

11 is a vacuum chamber or reservoir of sufficient size, which may be located in the 45 box or elsewhere. 12 is a suction line entering the vacuum chamber, and 13 are branches to the several siphon pipes 8. The siphon lines are normally closed off from the vacuum chamber by spring-closed valves 14 placed in 50 the several suction lines 13.

This valve means is of a selective nature, or of such nature that any one of the valves can be opened, but not more than one at a time. In the arrangement illustrated, an 55 operating lever 15 is slidable along a shaft 16 to any one of a number of positions, in which it can be rocked to act upon any one of the valves 14 and not upon others, a shield or enclosure 17 being preferably provided to 60 guard against undesired access to the valves.

The vacuum chamber has a line 18 which leads to a power exhaust pump, not shown, this line having a valve 19 to prevent loss of vacuum. A hand pump 20 is also connected 65 with this chamber for use in emergency, the

conduit 21 of this pump likewise having a valve 22.

Each of the siphon lines 8 contains a check valve 23 at a point beyond the connection with the exhausting means, these check valves 70 being adapted to close automatically to inflow of air and to open automatically to outflow of liquid. The said valves may have light springs 24, and are located between the suction lines 13 and the common discharge 75 pipe 9.

Means are preferably provided for holding these check valves closed against liquid flow and for permitting any one of them to be released at a time, the others continuing 80 to be held closed. In other words, as in the case of the valves 14, a selective control is preferably arranged for. The particular construction may be widely varied. Each of the bodies 25 of the check-valves is shown 85 provided with a rock-shaft 26 passing through a stuffing-box and carrying arms 27 and 28, inside and outside the valve-body, respectively. The arm 27 is positioned so that it may bear against the valve stem to hold 90 the valve forcibly to its seat under the action of a strong spring 29 connected to the arm 28. An operating lever 30 slidable along a shaft 31 is adapted to act on any one of the arms 28, to the exclusion of others. A 95 suitable catch 33 which can be engaged with the lever 30 will hold any one of the springs 29 out of action, leaving the corresponding valve free to open to outflow of liquid.

The connections 13 from the siphon lines 100 8, through which air is exhausted from these lines, are provided with float-valves 34 which close automatically on the arrival of liquid, so as to prevent the liquid reaching the chamber 11 or the pump.

The chamber 11 is provided with a valved 105 drain pipe 35, which, as a matter of convenience, may enter the discharge pipe 9. This drain may be opened occasionally to draw off any condensation of vapors.

The operation of the system as described thus far will be evident. The chamber 11 having been previously exhausted to a sufficiently low pressure or partial vacuum, one of the check-valves 23 is unlocked or released, the others remaining locked or held closed by powerful spring pressure. Then the corresponding suction valve 14 is opened.

Air is thereby exhausted from the siphon line of the tank chamber which it is desired 110 to empty, and the siphonic flow is started. While the term "exhausted" or "exhausting" is used in this connection, it will be understood that it is necessary to reduce the pressure in the siphon only sufficiently to enable 115 atmospheric pressure to raise the liquid over the highest point of the siphon. By means of the vacuum tank this is accomplished very quickly and without effort on the part of the attendant.

As soon as the liquid reaches the float valve 34, this valve closes, and the attendant then closes the valve 14, or permits that valve to close under the action of its spring. The check-valve 23, which closed against the inflow of air, automatically opens to allow the liquid to flow through into the discharge pipe 9 and thence into the hose.

Manifestly, the check-valve 23 need not be released until after the liquid has arrived at this valve and has closed the float-valve 34.

The discharge pipe is provided with a shut-off valve 36.

Certain of the aspects of the invention are not limited to the employment of a vacuum chamber. It will be understood, therefore, that this chamber may be omitted with its advantages, and that the hand pump may be connected directly with the suction line 12. It is not desirable to have the engine of the vehicle running while deliveries are being made, or are about to be made, but a power pump driven from some source of power other than the engine might be directly connected with this line, if the vacuum chamber is not used.

It is customary to provide siphons with siphon-breaker valves. I have illustrated a special arrangement designed for the present system and having certain features of novelty.

Two sets of siphon-breaker lines are connected with the upper portions of the siphons 7, 8. One siphon-breaker line 37 extends rearward from each siphon into the control-box 5, there being as many of these lines as there are tank chambers. The other set of siphon-breaker lines 38, each connected with a different siphon, extend forwardly to the region of the front end of the tank, or to the vehicle cab. At the rear ends of the lines 37, inside the box, are valves 39. These valves have handles 40 for manual operation, which handles are in such relation to the door 6 that when the door is closed the valves 39 must all be open. When the control-box door is opened preparatory to making a delivery, the attendant must close the siphon-breaker valve 39 pertaining to the siphon of the tank chamber from which the delivery is to be made. The other valves 39 are left open.

A thermal device 41 is associated with the valves 39, or with parts operatively related thereto, so as to bring about automatically, in case of fire, the opening of any of these valves that may be closed at the time. The device illustrated comprises a movable part 42 in operative relation to the handles 40, a sufficiently strong spring 43 urging this part, a trigger 44 restraining the part against movement, and a fusible element 45 holding the trigger. When the element 45 is fused, the spring 43 is released to cause the part 42 to act on the lever of any one or more of

the valves 39 that may be closed, to open them.

The siphon-breaker lines 38 have valves 46 at their forward ends. These valves are ordinarily closed, whereas those at the rear end are ordinarily open. The valves 46 have handles 47 so that any or all of them can be quickly opened in case of emergency. Furthermore, a thermal device 50, similar to the thermal device 41, is provided for bringing about automatically the opening of these valves in event of fire or dangerous heat at this region.

A feature not heretofore referred to is the provision of check valves 48 in the upper portions of the uptake limbs 7 of the siphons. These valves may be in the form of fairly heavy balls resting at a distance below seats 49, against which they will close in event of the tank overturning. They are not affected either by suction in starting the siphon action or by the flow of liquid while a delivery is being made.

What I claim as new is:

1. In a system for discharging liquid from any one of the plurality of tank chambers by siphon action, a plurality of siphons having uptake limbs communicating with the several tank chambers, a common discharge conduit connected with the downtake limbs of all the siphons, means for exhausting air from the siphons, and means for operatively connecting the aforesaid means with any one of the siphons at points in the several siphons between the common conduit and the tank chambers.

2. In a system for discharging liquid from any one of a plurality of tank chambers by siphon action, a plurality of siphons having uptake limbs communicating with the several tank chambers, a common discharge conduit connected with the downtake limbs of all the siphons, means for exhausting air from the siphons, means for operatively connecting the aforesaid means with any one of the siphons at points in the several siphons between the common conduit and the tank chambers, and valve means for closing each siphon against entrance of air and against intercommunication with other siphons through the common conduit while air is being exhausted from the siphon.

3. In a system for discharging liquid from any one of the plurality of tank chambers by siphon action, a plurality of siphons having uptake limbs communicating with the several tank chambers, a common discharge conduit connected with the downtake limbs of all the siphons, means for exhausting air from the siphons, means for operatively connecting the aforesaid means with any one of the siphons at points in the several siphons between the common conduit and the tank chambers, valves in the several siphon lines between said points and the common conduit,

and a selective means for operating the valve of any line to the exclusion of others.

4. In a system for discharging liquid from any one of a plurality of tank chambers by siphon action, a plurality of siphons having uptake limbs communicating with the several tank chambers, a common discharge conduit connected with the downtake limbs of all the siphons, means for exhausting air from the siphons, means for operatively connecting the aforesaid means with any one of the siphons at points in the several siphons between the common conduit and the tank chambers, automatic check valves in the several siphon lines between said points and the common conduit adapted to close against inflow of air and to open to outflow of liquid, means for holding said check valves closed against outflow of liquid, and means for releasing the check valve of any line so that said valve will open to the outflow of liquid.

5. In a system for discharging liquid from any one of a plurality of tank chambers by siphon action, a plurality of siphons having uptake limbs communicating with the several tank chambers, a common discharge conduit connected with the downtake limbs of all the siphons, means for exhausting air from the siphons, means for operatively connecting the aforesaid means with any one of the siphons at points in the several siphons between the common conduit and the tank chambers, automatic check valves in the several siphon lines between said points and the common conduit adapted to close against inflow of air and to open to outflow of liquid, means for holding said check valves closed against outflow of liquid, and an operating device capable of releasing the check valve of any one of said lines to the exclusion of others.

6. In a system for discharging liquid from any one of a plurality of tank chambers by siphon action, a plurality of siphons having uptake limbs communicating with the several tank chambers, a common discharge conduit connected with the downtake limbs of all the siphons, means for exhausting air from the siphons, and valved suction lines connecting said means with the several siphons at points between the common conduit and the tank chambers.

7. In a system for discharging liquid from any one of a plurality of tank chambers by siphon action, a plurality of siphons having uptake limbs communicating with the several tank chambers, a common discharge conduit connected with the downtake limbs of all the siphons, means for exhausting air from the siphons, suction lines connecting said means with the several siphons at points between the common conduit and the tank chambers, valves in said suction lines, and a selective means for bringing about opening

of the valve of any one of said suction lines to the exclusion of others.

8. In a system for discharging liquid from any one of a plurality of tank chambers by siphon action, a plurality of siphons having uptake limbs communicating with the several tank chambers, a common discharge conduit connected with the downtake limbs of all the siphons, means for exhausting air from the siphons, suction lines connecting said means with the several siphons at points between the common conduit and the tank chambers, valves in said suction lines, a selective means for bringing about opening of the valve of any one of said lines to the exclusion of others, valves in the several siphon lines between the suction lines and the common conduit, and a selective means for bringing about opening of any one of the last-named valves to the exclusion of others.

9. In a system for discharging liquid from any one of a plurality of tank chambers by siphon action, a plurality of siphons having uptake limbs communicating with the several tank chambers, means for exhausting air from the siphons, a plurality of suction lines connecting said means with the several siphons, and valve means controlling said suction lines so that any one of them can be opened.

10. In a system for discharging liquid from any one of a plurality of tank chambers by siphon action, a plurality of siphons having uptake limbs communicating with the several tank chambers, means for exhausting air from the siphons, a plurality of suction lines connecting said means with the several siphons, and a selective valve means for opening any one of said suction lines to the exclusion of others.

11. In a system for discharging liquid from any one of a plurality of tank chambers by siphon action, a plurality of siphons having uptake limbs communicating with the several tank chambers, means for exhausting air from the siphons, a plurality of suction lines connecting said means with the several siphons, a selective valve means for bringing about opening of any one of said suction lines to the exclusion of others, valves in the siphon lines at points beyond said suction lines, and a selective means for bringing about opening of any one of the last-named valves to the exclusion of others.

12. In a system for discharging liquid from any one of a plurality of tank chambers by siphon action, a plurality of siphons having uptake limbs communicating with the several tank chambers, means for exhausting air from the siphons, means for operatively connecting the aforesaid means with any one of the siphons, valves in the siphon lines beyond the points of connection for said exhausting means, and a selective control for said valves.

13. In a system for discharging liquid from

any one of a plurality of tank chambers by siphon action, a plurality of siphons having uptake limbs communicating with the several tank chambers, means for exhausting air 5 from the siphons, means for operatively connecting the aforesaid means with any one of the siphons, check valves in the siphon lines beyond the points of connection for said exhausting means, means for holding said check 10 valves closed against outflow of liquid, and a selective means for releasing any one of said check valves to the exclusion of others so that it will open to the outflow of liquid.

14. In a system for discharging liquid from 15 any one of a plurality of tank chambers by siphon action, a plurality of siphons having uptake limbs communicating with the several tank chambers, means for exhausting air from the siphons, means for operatively connecting the aforesaid means with any one of the siphons, and means influenced by the arrival of liquid for automatically closing the communication between any of the siphons 20 and said exhausting means.

15. In a system for discharging liquid from any one of a plurality of tank chambers by siphon action, a plurality of siphons having uptake limbs communicating with the several tank chambers, a vacuum chamber with 25 means for exhausting the same and means for holding the vacuum in the chamber, and means for operatively connecting any one of the siphons with said vacuum chamber.

16. In a system for discharging liquid from 30 any one of a plurality of tank chambers by siphon action, a plurality of siphons having uptake limbs communicating with the several tank chambers, a vacuum chamber with means for exhausting the same and means for 35 holding vacuum in the chamber, means for operatively connecting any one of the siphons with said vacuum chamber, and means influenced by the arrival of liquid for automatically closing the communication between any 40 siphon and the vacuum chamber.

17. The combination with a tank, of a siphon communicating therewith, a rigid walled vacuum chamber of sufficient capacity for numerous operations of the siphon, means 45 for exhausting said chamber, means for holding vacuum therein, means for operatively connecting said chamber with the siphon, and means controlled by the liquid thus drawn from the body of liquid in the tank for automatically bringing about the closing of the 50 communication between the siphon and said chamber.

18. In a system for discharging liquid from 55 any one of a plurality of tank chambers by siphon action, a plurality of siphons having uptake limbs communicating with the several tank chambers, a common discharge conduit connected with the downtake limbs of all the siphons, means for exhausting air from 60 the siphons, means for operatively connecting

the aforesaid means with any one of the siphons at points in the several siphons between the common conduit and the tank chamber, valve means for closing each siphon against entrance of air and against intercommunication with other siphons through the common conduit while air is being exhausted from the siphon, siphon-breaker lines connected with the several siphons, and siphon-breaker valves in said siphon-breaker lines. 70 75

19. In a system for discharging liquid from any one of a plurality of tank chambers by siphon action, a plurality of siphons communicating with the several tank chambers, means for exhausting air from the siphons, 80 means for operatively connecting the aforesaid means with any one of the siphons exclusively, siphon-breaker lines connected with the several siphons, siphon-breaker valves in said siphon-breaker lines, manual control 85 means for said siphon-breaker valves, thermal means adapted to bring about automatic opening of said siphon-breaker valves, and a control-box door to which the valves of all said siphon-breaker lines are related in such 90 manner that said valves must be open when the door is closed.

20. In a system for discharging liquid from any one of a plurality of tank chambers by siphon action, a plurality of siphons communicating with the several tank chambers, means for exhausting air from the siphons, 95 means for operatively connecting the aforesaid means with any one of the siphons, siphon-breaker lines connected with the siphons and running in two sets to opposite ends of the tank, siphon-breaker valves in the remote portions of the two sets of siphon-breaker lines, manual means for controlling each set 100 of siphon-breaker valves, and thermal means 105 adapted to bring about opening of the valves of each set.
